UNITED STATES PATENT OFFICE

RENÉ DENOUX, OF PARIS, FRANCE

ACOUSTIC RECEIVER

Application filed December 19, 1929, Serial No. 415,321, and in France July 6, 1929.

My invention relates to improvements in acoustic receivers of the type used in connection with phonographs, loud-speakers, and analogous instruments.

5 One of the objects of my invention is to provide an improved sound reflector in a device of the character indicated.

Another object is to provide an improved form of sound conveyor in combination with 10 a reflector of the aperiodic type.

The particular feature of the sound conveying device is the fact that it is composed of two frusto-conical members disposed one within the other on the same axis, with 15 perforations provided in the inner member which allow the sound waves of the inner member to pass into the outer member, the sound waves arriving at the inner member.

This disposition allows me to discriminate 20 the waves in two sound bodies whose constants agree with high and low sounds.

The particular feature of the reflector is the fact that it is constituted by a polished 25 glass surface preferably cut out from a sphere, but which may be a plane surface if desired. With this device I am able to produce total reflection effects which assure a large output and the inertia due to the glass surface assures purity in the sound reflected. 30 When the spherical reflector is used, either the convex or concave side may be utilized according to the particular effects desired.

In the following description I shall not 35 allude to the particular device for producing the sound as the same has no particular bearing on my invention. My device is in the form of a unit which is readily adapted to any of the well-known acoustic devices such as the tone arm extending from the sound 40 box in a phonograph, for example.

45 My invention will be more readily understood by those skilled in the art in the following detailed description when taken in connection with the accompanying drawings forming part of this specification, and in which—

Fig. 1 is a vertical section taken along the line 1—1 of Fig. 2; and

50 Fig. 2 is a horizontal section taken along the line 2—2 of Fig. 1.

Referring to the drawings more in detail, I have shown at 1 a flanged tube leading to the sound producing diaphragm which has not been illustrated since it forms no particular part of my invention.

55 A flanged elbow 2 forms an extension of a frusto conical member 3. The tube 1 carries a sleeve 1^a mounted on balls 1^b. The sleeve 1^a carries a coupling sleeve 1^c extending through a bracket 2^b over which fits a flange 2^a of elbow 2. The flange bracket and sleeves are clamped together by means of a screw 2^c and a nut 2^d. Bracket 2^b is secured to the housing of the device by means of two screws 2^e. Fitted into the interior of member 3, is a frusto conical member 4. Adjacent the smaller end of member 4 is an annular indentation 5 through which and adjacent to and extending through the member 4 are perforations 5'. The purpose of the 70 indentation 5 is to provide a larger space between members 3 and 4 adjacent the holes 5'.

An open housing 7 receives the ends of 75 members 3 and 4 and directly in front of said members is disposed a glass sound reflector 6. A space 8 is provided between the member 3 and housing 7 by means of spacing pins 8'. Additional spacing pins 8' are provided between members 3 and 4. These 80 spacing pins, in addition to supporting members 3 and 4, prevent parasitic vibrations.

The glass reflector 6 is fitted into the end 85 wall 10 of the housing 7 and extending therethrough is a pin 9 having a conical head 11, preferably. The said pin 9 also extends through the wall 10 and through the wall of the instrument in which my device is used, a part of which is shown at 10'. The whole is clamped together by means of a screw 12, 90 screwed into pin 9 and beneath the head of which is inserted a washer 13.

The operation of my device is as follows:

The sound waves arrive from the sound producing device through the tube 1 and member 2 and set the sound transmitting medium consisting of the columns of air contained in members 3 and 4 into motion. Due to the different size and shape of the air columns a discrimination is produced in the 100

waves. The deeper ones do not mix with the more elevated ones as is usually the case with devices of this character in which the sound waves are led into a single conical member which gives way to interference and beats detrimental to the production of clear sounds.

As to my reflector, by utilizing glass, I provide a substance which is very inert and responds very rapidly, giving a very pure reproduction of sweet tone suitable particularly for speech and music.

It is to be understood that while I have described my reflector in connection with a double frusto-conical sound conveying tube, I may nevertheless employ the same with a single tube.

If it is desired to obtain a very voluminous reproduction, I may reverse the position of the concavo-convex reflector so that it becomes a convex-concave reflector in order to reflect all the sound waves to the exterior. In this case when the sound waves strike the reflector coming through one or both tubular members as above described, they strike against a convex surface and are reflected into the housing in fan shape. It is to be understood that I may change the radius of curvature to produce the result desired and even increase the same substantially to infinity so that a plane surface is produced. In this case under consideration the sound may be less pure but it is more voluminous.

My improved sound reflector 6 is constructed of polished glass and either a plane surface or a spherical concavo-convex surface cut from a sphere or vice versa, and constitutes a new industrial product.

Having thus described my invention what I claim as new and desire to secure by Letters Patent is:

1. An acoustic device of the type described comprising an open housing, a tapered tube having its large end opening into said housing, means at the small end of said tube for connecting a sound producing device thereto, spacing pins for securing the large end of said tube within said housing, a second tapered tube having its small end fitted within the small end of said first tube, and also having a series of perforations adjacent the small end thereof, a plurality of spacing pins for securing the large end of said second tube within the large end of said first tube in spaced relation thereto, and a sound reflector of polished glass disposed in said housing directly in front of said tubes.

2. An acoustic device of the type described comprising an open housing, a tapered tube having its large end opening into said housing, means at the small end of said tube for connecting a sound producing device thereto, spacing pins for securing the large end of said tube within said housing, a second tapered tube having its small end fitted within

the small end of said first tube, and also having a series of perforations adjacent the small end thereof, a plurality of spacing pins for securing the large end of said second tube within the large end of said first tube in spaced relation thereto, and a concavo-convex sound reflector of polished glass disposed in said housing directly in front of said tubes.

In testimony whereof I hereunto affix my signature.

RENÉ DENOUX.
